No. 639,153.

Patented Dec. 12, 1899.

J. V. & E. CUNNIFF & H. J. KERRIGAN.
LOOM TEMPLE.

(No Model.)

(Application filed Aug. 16, 1899.)

UNITED STATES PATENT OFFICE.

JOHN V. CUNNIF, EDWARD CUNNIF, AND HUGH J. KERRIGAN, OF NEW BEDFORD, MASSACHUSETTS, ASSIGNEES TO THE DRAPER COMPANY, OF PORTLAND, MAINE, AND HOPEDALE, MASSACHUSETTS.

LOOM-TEMPLE.

SPECIFICATION forming part of Letters Patent No. 639,153, dated December 12, 1899.

Application filed August 16, 1899. Serial No. 727,379. (No model.)

To all whom it may concern:

Be it known that we, JOHN V. CUNNIF, EDWARD CUNNIF, and HUGH J. KERRIGAN, of New Bedford, county of Bristol, State of Massachusetts, have invented an Improvement in Loom-Temples, of which the following description, in connection with the accompanying drawings, is a specification, like letters and figures on the drawings representing like parts.

Our invention has for its object the production of a novel temple for looms, means being provided for maintaining the temple-head yieldingly in operative position or retracted when it is desired to hold the temple-head back in inoperative position, while leaving the hands of the weaver free.

Figure 1 is a top or plan view of a loom-temple embodying one form of our invention with the head in operative position, the cap being partially broken out to show the cylindrical toothed roll. Fig. 2 is a partial longitudinal section thereof on the line $x-x$, Fig. 1, the end of the cap or pod being shown in elevation. Fig. 3 is a rear end elevation of the stand, the shank, and coöperating parts. Fig. 4 is a sectional detail of the pod, cap, and roll on the line $x'-x'$, Fig. 2. Fig. 5 is an end view of the temple-roll, showing the removable toothed blades, the retaining means therefor being omitted; and Fig. 6 is a side elevation of one of the toothed blades of the roll.

The stand A is provided with longitudinal internal guides A, (see Fig. 3,) formed in the upper portions of depending cheeks A², connected at their rear ends by a cross-piece A³, apertured at 5 for a purpose to be described, the cheeks having at their lower edges ribs 6 to enter an undercut groove 3 in a block a, the stand being adjustably held in the block by a set-screw 7, bearing against a thin plate or shin 8, interposed between one of the ribs 6 and the adjacent wall of the groove 3. The under face of the block a has an undercut transverse groove 10 to receive a correspondingly-shaped supporting-plate A^X, on which the stand as a whole is adjustable in a lateral direction, a set-screw 12 and bearing-plate 13 holding the stand adjusted.

The shank B' of the temple-head enters and is longitudinally movable in the guides A' of

the stand, the rear end of the shank being increased in width to form shoulders b 25, which bear against shoulders 25 at the rear ends of 55 the guides to limit the outward movement of the shank.

The top of the stand is longitudinally slotted at a', Fig. 2, to receive the depending arm c' of a bent lever, the other arm c extending 60 above the stand, the lever constituting a controller for the shank, as will appear, and fulcrumed at c^X in ears a² on the stand. As shown in Fig. 2, the arm c' passes through a longitudinal slot b^X in the stand, and it has 65 attached to it one end of a coiled spring S, the other end of the spring being fastened to a depending lug b at the rear end of the shank B', the length of the spring being such that when the controller is in normal position (see 70 full lines, Fig. 2) the spring will be under sufficient tension to maintain the shank and temple-head in operative position. When, however, the controller is thrown into dotted-line position, Fig. 2, the spring will be compressed sufficiently to act upon the lug b and 75 retract the shank into the position shown by dotted lines, Fig. 2, the controller being past dead-center, the lug b moving through the opening 5 of the cross-piece A³ of the stand. 80 The controller c' thus operates through the spring to maintain the temple-head in operative position or retracted, as may be desired.

In order to keep the controller in normal position, so that the shank will be projected 85 by the spring, we provide a locking device, represented as a latch d, notched at d' to overhang and receive the arm c and pivoted at d^X on a lateral projection a³ of one of the ears a² of the stand, the latch being prolonged to 90 form an operating-handle d² and reduced at 30, Fig. 2, to pass under the projection a³. The face of the upturned end of the latch above the notch d', is convexed, as at d³, in order to act as a cam when engaged by the arm c as 95 the controller is moved into normal position, a spring s^X, Fig. 1, normally acting to press the latch inward toward the controller.

When it is desired to retract the temple-head, the latch d is retracted, releasing the 100 arm c of the controller, which immediately rises above the notched portion of the latch by reason of the tension of the spring S, and then the weaver swings the controller over

into dotted-line position, Fig. 2, retracting the shank and temple-head, as described, and maintaining it back. When the carrier is returned to normal position, the latch yields as the arm *c* passes over the cam-face *d*³ and into the notch *d*', when the controller is locked.

The pod *B*, having a depending leg *b*' to be struck by the lay as it beats up, is secured to or forms a part of the outer end of the shank *B*', and it has a recess to receive a rounded shoulder *f* of the cap *F*, which latter is mounted to rock on a pivot *b*² which, as herein represented, also forms a support for the cylindrical toothed roll *R*.

Referring to Fig. 2, the cap is shown as provided at its inner side with a rearwardly-extended ear *f*^x, between which and the top of the adjacent part of the shank is interposed a spring *s*⁵, which lifts the ear and tips the cap on its fulcrum *b*², to depress the outer edge *f*' of the cap. A headed and preferably screw-threaded stud 40, passed loosely through the ear and into the stand, acts as a stop to limit the spring-induced movement of the cap.

The cloth passes between the edges of the cap and pod, over the toothed roll, and out beneath the edge *f*' of the cap, the lifting tendency of the cloth to separate from the teeth being yieldingly counteracted by the spring *s*⁵.

The pivot *b*² is shown as extended through from one to the other end of the pod and threaded at *b*⁴ to enter a threaded hole in the upturned end *b*⁵ of the pod, the roll being rotatably mounted on said pivot.

We have herein shown the roll as comprising a body portion, a plurality of detachable toothed blades, and means to retain the blades in place on the body portion, the latter being shown as a cylinder *r*, longitudinally bored to receive the pivot *b*² and having its ends reduced, as at *r*', and exteriorly threaded. (See Fig. 4.) Longitudinal grooves or seats are made in the body to receive each a toothed metal blade *r*², the blades having their ends notched, as at *r*³, (see Fig. 6,) the blades being substantially as long as the body, exclusive of its reduced ends *r*'. Retaining rings or collars *r*⁴, having on their inner faces annular ribs *r*⁵, are slipped onto the extensions *r*' of the body portion and against the ends of the blades, the ribs *r*⁵ entering the notches *r*³ of the latter to hold the blades in position on the body, and to prevent removal of the rings or collars nuts *r*⁶ are screwed upon the extensions *r*' up snugly against the rings, thereby firmly holding the blades in place, yet permitting of their ready removal should one or more teeth of a blade or blades become bent or broken. In such event the notches

and rings or collars are loosened sufficiently to permit the withdrawal of the injured blade and a new one is inserted, after which the blade-retaining devices are secured in place.

The mode of construction of the roll obviates the accurate construction and machining necessary where the teeth are inserted separately.

Having fully described our invention, what we claim, and desire to secure by Letters Patent, is—

1. In a loom-temple, a stand, a temple-head having a shank longitudinally movable in the stand, a spring to normally maintain the shank extended, a controller for the latter, operative through the spring to maintain the head in operative position, or retracted, and a lock to retain the controller in normal position.

2. In a loom-temple, a temple-head having a shank, a stand in which the shank is longitudinally movable, a spring connected at one end with the shank to normally maintain the head in operative position, and a controller pivotally mounted on the stand and connected with the other end of the spring, the controller when in normal position subjecting the spring to tension to retain the shank extended, and when in abnormal position operating through said spring to maintain the shank retracted.

3. In a loom-temple, a temple-head having a longitudinally-slotted shank, a stand provided with a guide for and in which the shank is reciprocable, a pivoted controller mounted on the stand and depending through the slot in the shank, and a spring attached at one end to the depending part of the controller and at its other end to the rear end of the shank, the controller in normal position stretching the spring to maintain the shank extended, movement of the controller into abnormal position acting through the spring to retract the shank.

4. In a loom-temple, a temple-head having a longitudinally-slotted shank, a stand provided with a guide for and in which the shank is reciprocable, a bent lever pivoted on the stand and having one arm extended through the slot of and below the shank, a spring connecting said arm and the rear end of the shank, and a spring-latch to engage the other lever-arm and maintain it in normal position with the spring under tension, to extend the shank, release and shifting of the lever acting through the spring to retract the shank.

5. In a loom-temple, a stand, a temple-head having a shank longitudinally movable in the stand, a spring attached at one end to the rear end of the shank, and a movable member mounted on the stand between the temple-head and the rear end of the stand, to which the other end of the spring is attached, movement of the said member subjecting the spring to tension or compression, to thereby extend or retract the shank, respectively.

In testimony whereof we have signed our names to this specification in the presence of two subscribing witnesses.

JOHN V. CUNNIF. EDWARD CUNNIF. HUGH J. KERRIGAN.
